Attorney.

UNITED STATES PATENT OFFICE.

HARRY R. STEVENS, OF BALTIMORE, MARYLAND.

SANITARY BOTTLE CLOSURE.

Application filed December 18, 1922. Serial No. 607,580.

To all whom it may concern:

Be it known that I, HARRY R. STEVENS, a citizen of the United States, residing at Baltimore city, State of Maryland, have invented certain new and useful Improvements in Sanitary Bottle Closures, of which the following is a specification.

The device forming the subject matter of this application is a closure for milk bottles and the like, and is of that general form in which a cap is seated within an annular member adapted to fit on the top of a bottle, both the cap and the annular member being made of cardboard, paper or some similar substance, and being rendered impervious to moisture by a coating of paraffin or a like sealing medium.

The invention aims to provide a novel construction whereby one of the cooperating members of the closure is so constructed that a part thereof is absorbent and exposed to the moistening action of the contents of the bottle, the absorbent part of said member of the closure being permitted to swell, and to effect a tight joint.

It is within the province of the disclosure to improve generally, and to enhance the utility of, devices of that type to which the present invention appertains.

Although a preferred embodiment of the invention is shown in the drawings, a mechanic, working within the scope of what is claimed, may make changes in the precise form depicted and described, without departing from the spirit of the invention.

In the drawings: Figure 1 shows in elevation, a device constructed in accordance with the invention, mounted on a bottle; Figure 2 is a section on the line 2-2 of Figure 1; Figure 3 is a top plan; Figure 4 is a sectional detail enlarged from Figure 2; Figure 5 is a section similar to Figure 2, but showing a modification.

In Figures 1, 2, 3, and 4, the numeral 1 marks a bottle or like container, provided at its top with a bead 2 and having an internal shoulder 3. An annular member 4, which is trough-shaped in cross-section, receives the bead 2. Within the annular mem-

ber 4, a cap 5 fits closely. The annular member 4 and the cap 5 are made of cardboard, paper or some similar material which will absorb moisture and swell. The annular member 4 is coated throughout its major portion with paraffin or the like, as indicated at 7, a part of the annular member being devoid of paraffin as shown at 8, to define an absorbent expansible lip. The cap 5 is entirely coated with paraffin as shown at 6. If necessary, the annular member 4 and the cap 5 may be spaced slightly from the shoulder 3, as shown at 9, to permit the liquid in the bottle 1 to have access to the lip 8 of the annular member; although the aforesaid spacing is not necessary in all cases. The liquid in the bottle 1 moistens the lip 8, which is not coated with the sealing medium; and the lip expands, the cap 5 being tightly bound at its periphery, and an hermetic joint resulting.

In the form depicted in Figure 5, parts hereinbefore described have been designated by numerals previously used, with the suffix "a". The modification consists in providing the lip 8 of the annular member 4^a with an inwardly extended flange 10, prolonged beneath the cap 5^a and engaged between the cap and the shoulder 3^a, the said flange being devoid of sealing medium, and being exposed to the contents of the bottle.

The paraffin or other sealing medium is of inappreciable thickness and no attempt has been made to show it, saving in Figure 4, wherein the thickness of the sealing medium has been exaggerated.

Having thus described the invention, what is claimed is:-

The combination with a cap, of a bottle mouth protecting member extending around the cap and having its faces impervious to moisture, that portion between said faces being expansible under the action of moisture, said member having its expansible portion exposed at one edge to the contents of the bottle and expansible by moisture to bind upon and hold the cap.

In testimony whereof I affix my signature.
HARRY R. STEVENS.
